JOSEPH SILVIO

BY *Theodore W. Miller* ATTORNEY

UNITED STATES PATENT OFFICE

JOSEPH SILVIO, OF CHICAGO, ILLINOIS

BED BRACKET

Application filed February 13, 1931. Serial No. 515,495.

This invention relates to bed brackets.

In the past beds of the type employing bed slats transversely of the longitudinal frame elements of the bed have as a rule been provided with longitudinal strips extending along the bottom edge of the inner space of said elements for supporting said slats. Such an arrangement was subject to many objections as the slats frequently became sufficiently bowed or slipped out of the notches provided for them in the supporting strips and became disconnected from the longitudinal frame elements of the bed. Metallic brackets have been used in the past to take the place of these strips for retaining the slats more satisfactorily but the construction of these brackets has usually been such as to prohibit their use in the highly competitive business of bed manufacturing because of the expense involved, the brackets having been as a rule in the form of castings requiring considerable machining.

It is accordingly the primary object of this invention to provide a bed bracket for satisfactorily supporting and retaining the bed slats which may be economically manufactured and utilized in the assembly of the finished bed.

Other and further objects of this invention will be apparent as the same becomes better understood from an examination of the specification and claims in conjunction with the accompanying drawings, wherein—

Fig. 1 is a perspective detail view of a completed bracket involving this invention;

Fig. 2 is a fragmentary detail perspective view of a portion of a bed containing the bracket; and

Fig. 3 is a development view, showing a strip of sheet metal from which the bracket is struck.

Referring to the drawings more particularly, reference character 1 designates a strip of sheet metal struck in the form of a bracket. The ends of the bracket 1 are apertured at 2 to receive screws 3 for attaching the brackets 1 to the opposite inner faces of longitudinal frame elements 4 of the bed.

The bracket 1 is struck from a strip of sheet metal 5 shown in development in Fig. 3, the

strip being folded along the dotted lines shown in said figure in the dies (not shown) to provide the construction shown in Fig. 1, the central portion 6 of the strip forming a shoulder 6^a on the bracket on which the end of the bed slat 7 rests and the triangular sections 7 and 8 on opposite sides of the portion 6 forming side walls 7^a of the bracket. The walls 7^a engage the sides of the slats.

The bottom of the brackets 1 may each be provided with an aperture 9 for a screw (not shown) for entering the slats and preventing them from slipping out when bowed down by the weight of the bed spring (not shown).

The advantages and use of the afore-described bracket will be apparent without further detail.

I am aware that many changes may be made without departing from the principles of this invention and I do not wish to be limited to the details described.

I claim:—

1. A supporting bracket consisting of sheet metal of uniform thickness comprising a pair of vertical faces one at either end adapted to be attached to a supporting surface, a central portion disposed horizontally adapted to support a member desired to be supported by said device, and a pair of juxtaposed integral walls at either side of said central portion, the inner wall of each pair adapted to engage one side of said member, the bracket parts being integral.

2. A supporting bracket consisting of sheet metal of uniform thickness comprising a pair of aligned vertical faces one at either end adapted to be attached to a supporting surface, a rectangular central portion disposed horizontally adapted to support a member desired to be supported by said device, and a pair of juxtaposed triangular walls at either side of said central portion, the inner wall of each pair adapted to engage one side of said member, said faces, walls and central portion being integral.

In witness whereof, I hereunto subscribe my name this 10th day of Feb., A. D., 1931.

JOSEPH SILVIO.
